UNITED STATES PATENT OFFICE.

NICHOLAS O. KENNIKER, OF CHICAGO, ILLINOIS, ASSIGNOR TO DURABLE BOX CO., OF CHICAGO, ILLINOIS, A CORPORATION OF ILLINOIS.

EASTENER FOR BOXES.

1,290,230.

Specification of Letters Patent.

Patented Jan. 7, 1919.

Application filed April 18, 1916. Serial No. 91,880.

To all whom it may concern:

Be it known that I, NICHOLAS O. KENNIKER, a citizen of the United States, residing at Chicago, in the county of Cook and State 5 of Illinois, have invented certain new and useful Improvements in Fasteners for Boxes, of which the following is a description.

My invention belongs to that general 10 class of boxes known as knock-down boxes, in which the several parts may be disconnected from one another, stored and shipped, and may be again readily connected in proper relation for use. It particularly belongs to that class of knock-down boxes, 15 in which the end and side walls are provided with transverse cleats near the ends thereof. It has for its object the construction of a strong and serviceable box of the character 20 described which may be constructed at a minimum expense.

To this end my invention consists in the novel construction, arrangement and combination of parts herein shown and described, 25 and more particularly pointed out in the claims.

In the drawings, wherein like reference characters indicate like or corresponding parts,

30 Figure 1 is a perspective view of the preferred form of connecting means of my invention;

Fig. 2 is a sectional view showing the device properly positioned upon the approximate 35 cleats of the walls of the box, the dotted lines showing the manner of connecting the parts;

Fig. 3 is a similar view, showing the two proximate walls of the box bound together 40 in proper relation;

Fig. 4 is a slightly modified form;

Fig. 5 is a perspective view of a box, illustrating the construction of a box with my improved devices;

45 Fig. 6 is a plan view of the preferred form of connecting member;

Fig. 7 is a sectional end view taken from the left of Fig. 6; and

Figs. 8 and 9 are detail views illustrating 50 the preferred manner of securing the devices at the final or fourth corner as the box is set up.

In the drawings, 1—1 are the free legs of a connecting device constructed of rod or suitable wire, extending in the same general 55 direction, connected together by the section 2, thus forming a loop. 3—3 are the extending legs or the coöperating part, in which the connecting section 4 is bent over to form a hook adapted to engage the section 2, and 60 thus connect the two. In addition the free ends are bent at an angle, as at 5, and extended a distance substantially the thickness of the cleat on the box members, and thence bent at another angle, as at 6, the 65 free end extending backward as at 7, and adapted to be positioned in a suitable groove or aperture formed between the cleat and the body of the box, as shown in Fig. 2. In this figure, 8—8 are the approximate 70 walls of the box, notched together as at 9 to prevent endwise movement of one on the other. 10—10 are the transverse cleats on the walls of the box, which are firmly secured to the walls in any preferred manner, 75 the grain of the cleats usually crossing the grain of the material in the wall of the box. That portion of the device which extends across the top of the cleats, and which is marked 1 and 3, is embedded in the cleat by 80 means of a suitable groove formed therein, while the free ends 7, as before stated, are bent back and seated in suitable snugly fitting grooves, as shown, formed in the cleat, 85 thus firmly embedding the free ends in the cleat.

Fig. 3 clearly shows the position of the parts where the corner is formed and bound by the wire connecting devices, as stated.

It is obvious that in a box of the character 90 described this method is sufficient for three corners of the box. The fourth corner, however, it will be necessary to assemble somewhat differently, owing to the fact that with three corners thus locked together, the walls 95 at the fourth corner cannot be made to take the position shown indicated in Fig. 2; consequently the free ends of either one or both of the connecting members, preferably one, may be passed through suitable apertures 11 100 in the wall, and be formed with a loop 12 on the end thereof. The pin 13, or equivalent part, extending through the loops inside the wall, serves to bind the part in position,

and to complete the locking of the several walls of the complete box together. While thus assembling the side walls of the box the bottom and top are properly positioned 5 and secured in any preferred manner.

In securing the last mentioned device shown in Figs. 8 and 9, the box may be assembled except at that corner, and one member placed in position therein as shown at 10 the bottom of Fig. 3. The other member may then be hooked into the hook formed by the first mentioned member, and the free end extending through the wall 8, as indicated in the Fig. 8, and the vertical pin 13, 15 secures the whole strongly in position, completing the interlocking operation.

Supplemental binding means may be employed in a box of this character, if desired, thus, as shown in Fig. 4, a single wire or 20 rod 14, having its free ends 15 similarly bent, may have the ends properly inserted, similarly as the parts are shown in Fig. 2, and as the corner is brought to a right angle position shown in Fig. 3, the supplemental 25 binding wire 14 will be bent around the corner and strained into position. This straining action is possible with all of the devices, and is desirable in forming up the box, adding greatly to its rigidity and 30 strength. The proportion and sizes of the various parts are particularly determined with this object in view.

Thus, in the preferred form shown in Fig. 2, the double locking device may be employed near the ends of the cleats, while the supplemental binding wire 14 may be employed midway between the two, or may be increased in number if preferred.

In Fig. 6 the free ends as shown, are also 40 bent outward at an angle from the main body of the wire, the ends thus engaging with the cleat 10 at a greater distance from one another. Fig. 7 clearly shows this, 16 being the free ends of the engaging member bent at an angle as stated.

It will be seen from this description that the connecting means engaging with the cleat only, the latter should be firmly secured to the side and end walls of the box. The 50 connecting means are also preferably embedded in the cleats, as stated, and sized to rigidly bind and maintain the corners of the box. The interlocking corners 9 prevent any endwise movement of one wall upon the other. The side and end walls of the box proper are not perforated for the reception 55 of the locking members, and the cleats are firmly nailed to the walls with the nails clenched, thus giving great strength and rigidity to the completed box.

Having thus described my invention, it is obvious that various immaterial modifications may be made in the same without departing from the spirit of my invention;

hence I do not wish to be understood as 65 limiting myself to the exact form, construction, arrangement and combination of parts herein shown and described or uses mentioned.

What I claim as new and desire to secure 70 by Letters Patent is:—

1. The combination with knock-down box structures comprising side sections having transverse cleats at the adjoining ends thereof, of means for securing in angular relation 75 the corner portions of adjoining sections, said means comprising two U-shaped wire coupling members, each member adapted to be secured at its inner end portions to one of the side sections of the box, and said members being formed at their outer ends with portions to interlock with each other, one of said U-shaped members having intermediate parallel leg portions to lie flat against the outer face of the cleat of one of 85 the box sections and having its free end portions bent back and thence forward to provide return bend portions to extend around one edge face of the cleat and between the inner face of the cleat and the adjoining outer face of the box section. 90

2. The combination with knock-down box structures, comprising side sections having transverse cleats at the adjoining ends thereof, of means for securing in angular relation 95 the corner portions of adjoining sections, said means comprising two U-shaped wire coupling members, each member being adapted to be secured at its inner end portions to one of the side sections of the box, and said members being formed at their outer ends with portions to inter-lock with each other, one of said U-shaped members having intermediate parallel leg portions to lie flat against the outer face of the cleat of one of 100 the box sections, and having its inner end portions bent back and then forward to provide return bend portions to extend around one edge face of the cleat and between the inner face of the cleat and the adjoining outer face of the box section, said outer end portion of the member being bent down to 105 engage over the other end face of the cleat. 110

3. The combination with knock-down box structures comprising side sections having transverse cleats at the adjoining ends thereof, of means for securing in angular relation 115 the corner portions of adjoining sections, said means comprising two U-shaped wire coupling members, each member adapted to be secured at its inner ends to one of the side sections of the box and said members being formed at their outer ends with portions to inter-lock with each other, one of 120 said U-shaped members having intermediate parallel leg portions to lie flat against the outer face of the cleat of one of the box sections, and having its inner end portions 125

bent back and downwardly at an angle to the plane of the parallel portions, and thence forward to provide offset return bend portions to extend around one edge face of the 5 cleat and between the inner face of the cleat and the adjoining outer face of the box section.

In testimony whereof, I have hereunto signed my name in the presence of two subscribing witnesses.

NICHOLAS O. KENNIKER.
